(57) **CLAIM**

The ornamental design for an exterior lighting for aircrafts, as shown and described.

DESCRIPTION

FIG. 1 is a perspective view of an exterior lighting for aircrafts, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another perspective view thereof, in which a lamp is shown in an open position.

FIG. 9 is an enlarged view of portion 9 indicated in FIG. 1.

FIG. 10 is an enlarged view of portion 10 indicated in FIG. 3; and,

FIG. 11 is an enlarged view of portion 11 indicated in FIG. 4.

The broken lines depict portions of the exterior lighting for aircrafts that form no part of the claimed design.

1 Claim, 11 Drawing Sheets
